(57) **CLAIM**

The ornamental design for a milk maker, as shown and described.

DESCRIPTION

FIG. 1 is a front and top perspective view of a milk maker, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged perspective view of detail "9" identified in FIG. 1;

FIG. 10 is an enlarged perspective view of detail "10" identified in FIG. 2;

FIG. 11 is an enlarged perspective view of detail "11" identified in FIG. 3; and,

FIG. 12 is an enlarged perspective view of detail "12" identified in FIG. 5.

The dashed lines in the figures illustrate portions of the milk maker that form no part of the claimed design. The dash dot dash lines in FIGS. 1, 2, 3, 5, 9, 10, 11 and 12 are for the purpose of illustrating the enlarged views indicators and form no part of the claimed design.

1 Claim, 12 Drawing Sheets(56)
